A. V. DICKEY.

AIR GUN.

APPLICATION FILED NOV. 30, 1914.

1,191,877.

Patented July 18, 1916

UNITED STATES PATENT OFFICE.

ARTHUR V. DICKEY, OF SEATTLE, WASHINGTON

AIR-GUN.

1,191,877.

Specification of Letters Patent. Patented July 18, 1916.

Application filed November 30, 1914. Serial No. 874,668.

To all whom it may concern:

Be it known that I, ARTHUR V. DICKEY, a citizen of the United States, residing at Seattle, in the county of King and State of Washington, have invented certain new and useful Improvements in Air-Guns, of which the following is a specification.

This invention relates to air guns and specifically to improvements in the gun of this type illustrated and described in United States Patent No. 1,026,303, issued to me May 14, 1912; and the object of the invention is to simplify and perfect the construction of such devices in various particulars and renders them more serviceable and convenient to operate.

The invention consists in the combinations of the various devices, the construction and operation of which are hereinafter set forth in detail with reference to the accompanying drawings forming part of this specification.

In the drawings, Figure 1 is a vertical longitudinal section of an air-gun embodying the present invention. Fig. 2 is a top plan view thereof. Fig. 3 is a side elevation of the same. Fig. 4 is a longitudinal elevational view, partly in section, of the breech-block shown detached.

The gun barrel 2 is secured to a junction member 3 having a cylindrical cavity to receive a rotary breech-block 4. Extending forwardly from said cavity is a port 5 in axial alinement with the bore of the gun-barrel, and at the rear of the cavity is an opening into the magazine for the projectiles B. At the top of said cavity is an opening 6 through which projectiles may be introduced, and at its lower side the cavity communicates with an air reservoir 7 through a passage 8. The breech-block 4 has formed therein a passage with openings 9 and 10 arranged in rectangular relations, as shown in Fig. 1. The air-reservoir 7 is connected by a duct 11 with a chamber 12 which, in turn, is connected with the discharge end of a pump cylinder 13. The spring-pressed check-valve 14 is adapted to prevent any return of air from the chamber 12 to the pump. A relief valve, indicated by 15, is utilized to exhaust the air from the pump into the external atmosphere, and is provided with a stem 16 whereby opening or closing of the valve is effected. The re-

ferred to projectile magazine is in the nature of a tube 17 which is inserted in a tubular casing 18 and secured therein by a bayonet connection comprising a pin 17¹ on the tube engaging in an angular slot 18¹ provided in the casing.

The projectiles are urged forwardly and against the peripheral surface of the breech-block 4 by means of a spring 20 acting against the projectiles through the medium of a follower 21. The controlling valve 22 is yieldingly held against a seat provided in the air-passage 8 by a spring 23. Connected to the controlling valve 22 is a forwardly projecting stem 24 which serves as the firing pin and extends through an opening in the member 3 into a cylindrical tube 25 which is subjacent to the gun barrel. Within the tube 25 is a hammer 26 which is operated by a main-spring 27 interposed between said hammer and a plug 28 provided with screw-threads, and engaging screw-threads within the tube in adjustable positions to regulate the effective power of the spring. The power of this main-spring is, however, less than that of the spring 23, so that while the momentum of the hammer will be sufficient when striking the firing pin 24 to unseat the controlling valve, the spring 23 quickly asserts its superior power to re-seat the valve and thus prevent any waste of the compressed air when discharging the gun. The momentum of the hammer is, moreover, influenced by means which I provide for regulating the throw of the hammer so that the controlling valve may be opened to a greater or less extent to release from the reservoir various quantities of compressed air according to the velocity at which a projectile is discharged; to which end the hammer-block is provided in its lower side with a series of spaced notches 29, 29¹ and 29² which are selectively engaged by detent 30 provided on an arm of a bell-crank lever 31 to releasably hold the hammer at predetermined distances from the firing pin. The lever 31 is fulcrumed by a pivotal pin 32 and has a depending arm 31¹ which is connected by a pull-rod 33 with a trigger 34 which is fulcrumed to a pin 35.

The spring 36 acts against the trigger to retain the same and the lever 31 in operable positions. Hammer 26 has at one side a stud 37 which extends laterally through a

slot 38 provided in the tube 25 whereby the hammer is advanced into positions to be engaged by the detent 30 of the lever 31.

The hammer may be set in firing positions 5 by the operator grasping the stud 37 in his fingers and thereby pushing the block forward or through the medium of an actuator 39 which, upon being thrust forward, engages the stud and carries the block therewith. Said actuator is mounted for longitudinal reciprocating movements on a guide ridge 40 provided at the side of the air reservoir. At its upper edge, the actuator is provided with rack-teeth 41 and at a distance 15 in front thereof is a lug 42. The teeth 41 mesh with teeth 43 provided on the end of the breech-block, whereby the latter is rotated during the terminal portion of a forward movement of the actuator to carry 20 the opening 9 of the block passage into position to receive a projectile B from the magazine and also serves, during the early portion of a rearward movement of the actuator, to return the breech-block into the 25 position in which it is represented in Fig. 1.

When the actuator is thrust rearwardly, the lug 42 of the actuator encounters one of the teeth 43 of the breech-block to arrest the same in position to have the passage opening 9 thereof register with the barrel-bore. 30

To compensate for the different positions at which it is desired to set the hammer, the actuator is provided with a sleeve 39¹ for a rod 44 which is secured in adjusted position 35 by a set-screw 45. The actuator is reciprocated by means of a knob 39².

As shown in Fig. 4, the mouth 9¹ of the opening 9 of the breech-block passage is advantageously formed of a diameter greater 40 than the remainder of the passage so as to accommodate a projectile in such mouth of a size larger than would pass through the passage. The reference numeral 46 designates a relatively weak spring protruding 45 into the mouth 9¹ of said passage for preventing the accidental falling out of a projectile. The breech-block 4 is provided with a stem having a knurled head 47 whereby the block may be rotated to present the 50 opening 9 of its passage to the hole 6 when it is desired to supply a projectile thereto instead of from the magazine.

In order to accomplish the partial turning of the breech-block, the actuator must 55 first be shoved forward sufficient to withdraw the stop 42 out of the orbital path of the block teeth 43.

A pin 48, Fig. 4, protrudes from the periphery of the breech-block into a circumferential groove 49 (Fig. 2) formed in the member 3, said groove terminating at a shoulder 49¹ disposed to stop the rotation of the breech-block when the passage opening 9 thereof is in position to receive a 65 projectile from the magazine 17.

The pump plunger 50 is secured to an end of a piston rod 51 which is connected by a link 52 with a lever 53. This lever is fulcrumed at its forward end by a pin 54 to the underside of the gun-frame against 70 which it is laid when unemployed, as shown by full lines in Fig. 1. The lever serves as a pump handle to operate the plunger through the medium of the link 52 and rod 51. 75

The operation of the invention is as follows: The reservoir is charged with air under compression by means of the pump which is operated by swinging the lever handle 53, causing the air to be drawn into the cylinder 13 through inlet hole 56 when the plunger 50 is drawn to the forward end of the cylinder and expelling the air under pressure into and through the chamber 12 when the plunger is moved toward the other 85 end of the cylinder. When the reservoir and the communicating chamber are charged with air under considerable pressure, the lever-handle 53 is most conveniently moved against the gun-frame by opening the valve 90 15 for exhausting the air between the check-valve and the pump plunger.

To use the gun as a repeater, the actuator 39 is moved forward by the operator, thereby forcing the hammer 26 into a position 95 regulated by adjusting the extension or rod 44, at which it is desired to have the detent 30 engage a selected notch of the hammer. As this occurs, the teeth 41 of the actuator engage the teeth 43 on the breech-block, resulting in the turning of the latter approximately 180° or until the passage outlet 9 is in register with the magazine. A projectile is thereupon forced into the counterbore 9¹ of such outlet and is carried into position to enter the barrel when the breech-block is returned to its original position by the retraction of actuator 39. 100 105

To fire the gun, trigger 34 is pulled to effect the withdrawal of the detent 30 from 110 a hammer notch, as 29. The hammer being thus released, is driven rearwardly by the spring 27 striking the firing-pin 24 and by its momentum causes the controlling valve 22 to be forced back from its seat in 115 opposition to the spring 23. A blast of air is thus delivered through the breech-block passage to discharge the projectile. The spring 23, being stronger than the spring 27, is only momentarily overcome by the striking effect of the hammer and recovering, 120 serves to rapidly close the valve 23.

To employ the gun as a single shot rifle, the hammer is thrust forward into detent-engaging position by the operator pushing 125 it with the stem 37. The actuator is then moved to remove the stop 42 from the breech-block, which is then turned by the head 47 to move the outlet 9 beneath the hole 6 in the member 3, to receive a projectile 130

deposited thereon. The breech-block is then rotated back to carry the projectile into position to be driven through the barrel by an air-blast attained by a trigger pull, as 5 above explained.

To uncock the gun, the operator pulls the trigger with the finger of one hand while receiving the impact of the hammer, through stem 37, in his other hand, and allowing 10 the hammer to recede slowly against the firing-pin 24.

Having described my invention, what I claim, is—

1. In an air-gun of the class described, an air-reservoir, a valve for controlling the delivery of the air from said reservoir for discharging the gun, a hammer, springs for the hammer and valve, means to releasably hold the hammer in various positions relatively 15 to the valve, a reciprocatory actuator, and devices adjustably connected to said actuator whereby the hammer is movable thereby to any of the aforesaid positions with a uniform travel of the actuator.
2. In an air-gun, in combination, a pump, an air-storage reservoir, a magazine chamber axially alined with the gun-barrel, a rotatable breech block interposed between said magazine and said barrel and provided with 20 a passage adapted to register with the barrel of the rifle when in firing position, teeth formed upon an end of said breech-block, a reciprocable actuator provided with teeth adapted to engage said teeth upon the breech 25 block, means whereby said breech-block may be turned until said passage registers with the magazine, and means for admitting air 30
3. In an air gun of the class described, a barrel and air reservoir associated with the barrel, a rotary breech block positioned between the barrel and reservoir, a bullet compartment communicating with the breech block, teeth formed on the periphery of the projecting end of the breech block, and a rack bar slidably associated with said air reservoir adapted for engagement with the breech block teeth to rotate the breech block to cause the same to move to position to receive a bullet.

3. In an air-gun, in combination, a pump, an air-storage reservoir, a magazine chamber axially alined with the gun-barrel, a rotatable breech-block interposed between said magazine and said barrel and provided with a passage adapted to register with the barrel of the rifle when in firing position, teeth formed upon an end of said breech-block, a reciprocable actuator provided with teeth adapted to engage said teeth upon the breech-block, means whereby said breech-block may be turned until said passage registers with the magazine, and means for admitting air

to said passage from said storage reservoir to discharge a projectile.

3. In an air-gun, in combination, a pump, an air-storage reservoir, a magazine chamber axially alined with the gun-barrel, a rotatable breech-block interposed between said magazine and said barrel and provided with a passage adapted to register with the barrel of the rifle when in firing position, teeth formed upon an end of said breech-block, a reciprocable actuator provided with teeth adapted to engage said teeth upon the breech-block, means whereby said breech-block may be turned until said passage registers with the magazine, stops to limit the rotary movements of said breech-block, and means for admitting air to said passage from said storage reservoir to discharge a projectile.

4. In an air gun of the class described, a barrel and air reservoir associated with the barrel, a rotary breech block positioned between the barrel and reservoir, a bullet compartment communicating with the breech block, teeth formed on the periphery of the projecting end of the breech block, and a rack bar slidably associated with said air reservoir adapted for engagement with the breech block teeth to rotate the breech block to cause the same to move to position to receive a bullet.

Signed at Seattle, Wash., this 14th day of November, 1914.
